UNITED STATES PATENT OFFICE.

CARL TOBER, OF BERLIN-KARLSHORST, GERMANY.

BOBBIN-WINDING MACHINE.

Application filed July 1, 1922. Serial No. 572,115.

To all whom it may concern:

Be it known that I, CARL TOBER, a subject of the German Republic, residing at Berlin-Karlshorst, in Germany, have invented certain new and useful Improvements in a Bobbin-Winding Machine, of which the following is a specification.

My invention relates to bobbin-winding machines in which the traversing means consist in spiders rotating in opposite direction and alternately engaging the thread for guiding it from one end of the bobbin to the other. In the bobbin-winding machine according to the present invention, the spindle carrying the bobbin is positively rotated and has a definite constant or substantially constant rate of speed relative to the rotation of the said spiders. Moreover, the guiding face of the thread-guide provided between the said spiders and the bobbin is adjustable.

On the drawing herewith, on which I have shown my invention by way of illustration, Fig. 1 is a side elevation of the new bobbin-winding machine; Fig. 2 is a top view with the upper portion removed and a portion being broken away; Fig. 3 is a full top view; Fig. 4 is a front-view, while Fig. 5 is a diagrammatic view of a detail.

30 A belt 1 operated by the pulley 4 (Fig. 1) drives a pulley 20 secured to the spindle 12 which carries the bobbin 11 and is journaled in the bearing-sleeve 38. On the spindle 12 is also mounted a worm 25, which 35 is in mesh with a worm-gear 26 and carried by an oscillating arm 17. The latter is adapted to swing about the pivot pin 15 and also carries the thread-guide 10.

The latter is adjustable relative to the spindle 12 of the bobbin 11, and where bobbins are used having a rim, the arm 17 is so adjusted that the thread-guide 10 is at a small distance from the rim of the bobbin.

40 As shown in Fig. 5, the thread-guide 10 can also be adjusted so as to be held at a definite distance *w* from the circumference of the bobbin, i. e. at a distance which remains uniform while the bobbin is filled. To this end, there is provided opposite the 45 thread-guide 10 a roll 37 bearing against the circumference of the bobbin. As the circumference increases, the arm 17 carrying the thread-guide 10 is moved about its pivot

pin 15 by means of the lever 21 and link 22 so as to move the thread guide 10 a corresponding amount away from the bobbin, so that the distance *w* remains the same.

On the shaft of the worm-gear 26 is mounted also a pulley 28 (Figs. 1 and 2), from which passes a belt 23 over a pulley 29 (Fig. 4). The shaft of the latter carries a toothed gear 30 which is in mesh with a similar gear 6 (Fig. 3) which is carried on the end of the shaft 2 carrying the spider 3.

The shaft carrying the pulley 29 and toothed gear 30 is carried in the end of an arm 24 pivotally arranged on shaft 2 and from the other end of the arm 24 is suspended a weight 32 (Fig. 1) so that the belt 23 connecting the pulleys 28 and 29 is always kept under tension.

For holding the thread-guide 10 against the bobbin, a weight 39 (Figs. 2 and 4) is provided, from which a cord 40 passes over a sheave 41 journaled in a bracket 42. The cord 40 by means of a lever 43 and a link 44 so controls the oscillating movement of the arm 17, that the thread-guide 10 is held against the bobbin 11, the arrangement being such that as the circumference of the bobbin increases, the pull of the weight 39 on the arm 17 correspondingly decreases.

35 The journal supports 9 and 14 for the spiders 3 and 5 are secured to the oscillating arm 17 and can be arranged on a common base-plate capable of adjustment on the arm 17. The spider 5 is rotated opposite to the direction of rotation of the spider 3,—by a suitable gearing indicated at 45 in Fig. 1.

The pulleys 28 and 29 or the toothed gears 30 and 6 are exchangeable to provide for a change in speed of rotation, and the fingers of the spiders 3 and 5 can be likewise exchanged and adjusted as to their lengths.

I claim as my invention:

1. In a bobbin-winding machine, the combination of a rotary spindle adapted to carry the bobbin, means for positively driving the said spindle, a movable thread-guide, means for automatically adjusting the said guide relative to the said bobbin and oppositely rotating traversing members alternately engaging the thread.

2. In a bobbin-winding machine, the combination of a rotary spindle adapted to

carry the bobbin, means for positively driving the said spindle, oppositely rotating the traversing members, an oscillating arm carrying said traversing members, a thread-guide supported on the said arm, and means controlled by the circumference of the said bobbin for operating the said arm thereby adjusting the position of the said thread-guide relative to the said bobbin and the said traversing members. ¹⁰

In testimony whereof I have affixed my signature.

CARL TOBER.
